UNITED STATES PATENT OFFICE.

LUTE E. HINES, OF LIMA, OHIO.

OIL-BURNER.

1,121,500.

Specification of Letters Patent. Patented Dec. 15, 1914.

Application filed December 20, 1913. Serial No. 808,009.

To all whom it may concern:

Be it known that I, LUTE E. HINES, a citizen of the United States, residing at Lima, in the county of Allen and State of Ohio, 5 have invented certain new and useful Improvements in Oil-Burners, of which the following is a specification, reference being had therein to the accompanying drawing.

This invention relates to liquid gaseous 10 fuel burners and the principal object of the same is the production of an oil burner which is provided with efficient means for supplying air in connection with the oil supply, thereby supporting combustion.

15 Another object of this invention is the production of a casing for an oil burner which is provided with a plurality of air channels for providing each burner orifice with a support and independent supply of 20 air.

Another object of the invention is the production of a plurality of oil deflector plates which may be easily moved into position 25 above the burner orifices for catching and conveying oil to a portion of the device so that the same may be ignited.

With these and other objects in view, this 30 invention consists of certain novel combinations, constructions and arrangements of parts as will be hereinafter fully described and claimed.

In the accompanying drawings: Figure 1 is a top plan view of the oil burner. Fig. 2 is a side elevation of the invention. Fig. 3 is a detailed perspective view of the casing, the detachable portions of the device being removed. Fig. 4 is a horizontal section taken through the casing. Fig. 5 is a section taken on the line 5—5 of Fig. 2, 35 looking in direction of the arrow. Fig. 6 is a section taken on the line 6—6 of Fig. 1, looking in direction of the arrow. Fig. 7 is a top plan view of the invention showing the same carried by the grate of an ordinary 40 stove or furnace. Fig. 8 is a perspective view of the burner pipe. Fig. 9 is a perspective view of the burner pipes showing a slightly modified oil deflector used therewith. Fig. 10 is a sectional view taken 45 through one of the deflectors used in Fig. 9. Fig. 11 is a perspective view of a slightly modified form of a burner pipe. Fig. 12 is a side elevation of a slightly modified form 50 of the invention showing the same provided with a raised air inlet for allowing the same to be used in connection with a fur-

nace or similar device by placing the same upon the grate. Fig. 13 is a top plan view of the device disclosed in Fig. 12. Fig. 14 is a section taken on the line 14—14 of Fig. 12 55 looking in direction of the arrow. Fig. 15 is a perspective view of another form of burner pipe.

Referring to the accompanying drawings by numerals 1 indicates the base of the 60 burner which is provided with a back wall 2 and a short front wall 3.

The wall 2 carries a top 4 which terminates in a depending side 5 having a platform 6 which is integral with the front wall 70 3. The ends of the walls are connected with the end wall 7 which is of the same height as the rear wall 2 and extends so as to be formed upon the front wall 3 and extends 75 for a determined distance above the platform 6.

The opposite end of the front 3 is provided with an integral end 8 having an angularly extending portion 9 which is connected to the top 4 thereby leaving a space 80 between the portion 9 and the back or rear wall 2, as clearly disclosed in Fig. 4. Within this space there is formed an integral partition 10 which extends longitudinally of the top 4 and bottom 1 and is positioned 85 parallel to the back 2. This partition 10 is provided with an angularly extending portion 11 which is cut away to fit under the platform 6 as shown in Fig. 5. In forming the casing in this manner it will be seen 90 that an air chamber 11 is formed in one end of the casing which is supplied by the passage 12 while the air channel 13 supplies air to the chamber 14.

The platform 6 is provided with a plurality of openings 15 and 16 which constitute the burner openings. The opening 15 is formed in the platform 6 so as to communicate with the air chamber 11, while the opening 16 is formed to communicate with 100 the air chamber 14.

The burner pipes used in this device comprise a feed pipe 17 which rests within the enlarged notch 18 formed in the end 8, while the bent or elbow pipe 18' will bear against 105 the vertical plate 19 formed upon the end 7 for holding the supply pipe 17 in a central position upon the end. A secondary supply pipe 19' is connected to the pipe 18' 110 so as to extend parallel to the feed or supply pipe 17 and is provided at its opposite end with a diagonal bent or elbow pipe 20

which bears upon a block 21 carried by the platform 6. A burner pipe 22 is connected to the pipe 20 and in this pipe 22 the openings 22' for the expelling of the oil are formed. This pipe 22 is positioned within the notches 23 formed in the vertical collars 24 carried by the platform 6 for holding the burner pipe 22 in a central position upon the platform. By referring to Figs. 3, 5 10 and 6 it will be seen that the collars 24 are formed so as to surround the openings 15 and 16. By forming the plate 19 and the notch 18 in the end 8 as well as the notches 23 formed in the collars 24, the supply and 15 burner pipes will be held in their correct position upon the casing. A rod 25 rests in the socket 26 formed below the notch 18 while the opposite end bears in the pocket 27 formed in the end 7. This rod is provided with an angular handle 28 formed adjacent the end 8 thereby allowing the rod 25 to be pulled so as to slide, as indicated in dotted lines in Fig. 2. This rod carries a plurality of blaze deflecting plates 29 which 20 are adapted to slide so as to be moved over the openings 15 and 16, as shown in Figs. 2 and 5. As the oil passes up from the burner pipe 22, the same will be mixed with the air passing up through the openings 15 and 16 25 thereby causing the same to be ignited and as the blaze flames upwardly it will strike upon the reflector plates 29 thereby causing the blaze to spread upon the side portions of the plates.

30 An arm 30 having crank ends 31 bears at one end within a slot 32 and the opposite end within the aperture 33, thereby allowing the arm 30 to be swung upwardly by turning the finger 34. This arm is fixedly secured to the oil deflector plates 35 thereby 35 allowing these plates to be freely operated when desired. These oil deflector plates 35 are provided with flanges 36 upon their outer edges and which are opened, as shown 40 at 37 at one end. A central opening 38 is formed in each oil deflector plate 35 which is surrounded by a neck 39. When these plates are swung upwardly on the arm 30 so as to overhang the openings 15 and 16, the openings 38 will be positioned over the central portion of each opening 15 and 16 45 so that when the oil spouts upwardly from the burner pipe 22 it will pass through the openings 38 and then fall back upon the plate 35 since this plate 35 is swung upwardly it will be inclined toward its open end, as clearly disclosed in Fig. 6. The depending wall 5 carries a longitudinal flange 40 which extends upwardly to constitute a trough 41 so that when the oil passes through this plate 35 it will pass into the trough 41 and then through this trough 41 downwardly upon the platform 6 where it 50 may be ignited.

55 From the foregoing description it will be

seen that an efficient oil burner has been produced which is provided with simple means for supporting combustion while the same is provided with simple means for deflecting the blaze.

It will be seen by referring to Fig. 5 that the top 4 is provided with a box-like pocket 42 for the reception of a supply pipe 43 disclosed in Fig. 9. A secondary supply pipe 44 having the usual connections or elbows 45 75 is adapted to be used with this pipe 43 and also communicates with the burner pipe 46. When this form of a device is used, the pipe 43 will rest at one end within the pocket 42 while the burner pipe 46 will rest within the notches 23 formed in the collars 24. A plurality of sliding oil deflectors 47 may be used upon this form and may be operated by a straight rod 48 for sliding the same along the pipe 43. These sliding deflectors 80 47 each have a hollow body 49 and an aperture 50 through which the oil may pass. This body 49 is provided with a sloping bottom 51 for allowing the oil to flow therefrom into the trough 41. It will be noted 85 that the body 49 carries a lug 52 for allowing the same to freely slide along the pipe 43.

In Fig. 11 a slightly modified form of feed and burner pipes have been produced 95 wherein the feed pipe 53 is positioned directly above the burner pipe 54. This feed pipe is provided with a diagonal connection 55 which rests within the pocket 42 of the casing and the longitudinal secondary 100 supply pipe 56 is positioned above and to one side of the supply pipe 53 and is provided with a depending diagonal connection 57 which communicates with the burner pipe 54.

A still further form of feed and supply pipe is shown in Fig. 15 wherein the burner pipe 58 is positioned directly beneath the feed pipe 59. This feed pipe, however, is provided with an integral circular pipe 60 110 which is adapted to be heated by the burner pipe 58 and at the same time constitute a support for any article which may be placed above the blaze. By referring to Fig. 7, it will be seen that this device may be placed 115 upon the grate 61 of an ordinary stove 62. When this form is used, if it is so desired, the bottom 1 of the casing may be removed and air supplied to the air chambers 11 and 14 through the grate 61.

In Figs. 12, 13 and 14 a slightly modified casing has been produced having a hollow body 63 to which the raised air inlet 64 is integrally connected. This hollow body 63 is provided with a collar 24' having 125 notches 23'. The body is also provided with a vertical block 21' and an end 65 is provided with the plates 66 and 67 for supporting the feed pipe used in connection therewith. The upper portion of the body 63 130

carries a channel or trough 68 for the purpose above described. It will also be seen that the aperture 69 is provided in the end, while the end 70 is provided with a notch 71 for holding the feed pipe in its correct position upon the casing.

By carefully referring to Figs. 5 and 6 it will be seen that the gas deflecting plates 29 are positioned beneath the supply pipe 17 and are adapted to be used after the gas 10 17 has been generated and ignited and are to be slideable.

It will be seen that when it is desired to distribute the oil upon the top 6 and 15 upon the other portions of the device before the same is ignited the gas deflector plates are moved from above the openings by sliding the rod 25. The oil deflecting plate 35 may then be swung over the openings so 20 as to allow the oil to pass upwardly through the openings 38 so as to strike against the rod 25 thereby causing the oil to fall back upon the plates 35 where it will be guided to the trough 41 which will distribute the 25 same upon the top 6.

What is claimed as new, is:—

1. An oil burner comprising an elongated hollow casing, said casing provided with a platform, burner portions formed upon said 30 platform, burner pipes carried by said casing and overhanging said burner portions, said casing provided with a longitudinal partition terminating in an angular portion thereby forming air chambers within said 35 casing whereby said burner portions will be supplied with independent air so as to efficiently support combustion.

2. An oil burner comprising a casing, said casing provided with a reduced front portion, said front portion provided with openings having upstanding collars formed therearound and notches formed in said collars, a burner pipe carried by said collars within said notches thereby holding said 45 burner pipe in its correct position over said openings, said casing provided with means for supplying said openings with independent supplies of air, and means carried by said casing adapted to be moved into position to overhang said openings for constituting a blaze deflector when so desired.

3. An oil burner comprising a casing, said casing provided with a reduced forward portion having air openings formed therein, said forward portion provided with a vertical block, one portion of said casing provided with a vertical plate, a feed pipe extending longitudinally across the upper portion of said reduced forward portion of said 50 casing, said pipe adapted to bear against said vertical plate for holding said pipe in a central position, a burner pipe extending across said openings, said burner pipe provided with burner openings for allowing oil 55 to pass therethrough and mix with air pass-

ing through said air openings, and a diagonal pipe connecting said burner pipe with said feed pipe and resting upon said vertical block whereby said feed and burner pipes will be held in their correct position upon 70 said casing.

4. An oil burner comprising a casing, said casing provided with a reduced forward portion, air openings formed in said forward portion, means for supplying each air 75 opening with an independent air supply, a longitudinally extending trough formed upon said casing adjacent said forward reduced portion above and to one side of said air openings, end portions formed adjacent 80 said forward reduced portion of said casing, said ends provided with notches at their upper edges, a supply pipe resting within one of said notches, said supply pipe provided with a depending short pipe, a vertical 85 plate connected to one of said ends, said depending short pipe bearing against said vertical plate whereby said supply pipe will be held in its correct position, a secondary supply pipe connected to the lower end of said 90 depending short pipe so as to extend parallel to said first-mentioned supply pipe, a diagonal depending short pipe connected to the opposite end of said secondary supply 95 pipe, a vertical block carried by said forward reduced portion, said diagonal short pipe bearing upon said block whereby said secondary supply pipe will be held in its correct position, and a burner pipe connected to said last mentioned diagonal pipe and extending across said openings, said burner pipe provided with burner openings for allowing oil to pass therethrough and mix with the air passing through said air openings whereby the same may be ignited, a 100 rod pivotally secured to said ends, oil deflector plates having central openings carried by said rod and adapted to be swung over said air openings, whereby the inner ends of said plates will overhang said 105 trough whereby superfluous oil may pass through the central openings in said plates and be caught by said plates and be conveyed to said trough whereby oil may move to the end portions of said forward 110 reduced portion of said casing for allowing 115 the same to be ignited.

5. An oil burner comprising a casing, said casing provided with an open end, a plurality of air openings formed in said casing, 120 a burner pipe positioned above said air openings for supplying oil, a partition extending from said open end of said casing to a point adjacent the central portion of said casing, said partition provided with a laterally extending secondary partition thereby forming separate air chambers of each air opening whereby air may be passed into the open end of said casing and be supplied to one of said air openings independ- 125 130

ent of the remaining air openings for supporting combustion.

6. An oil burner comprising a casing, said casing provided with a reduced front portion having a plurality of air openings formed therein, ends formed at each end portion of said reduced portion of said casing so as to extend for a distance above said reduced portion, a supply pipe extending across said reduced portion, said supply pipe being provided with a burner pipe resting upon said reduced portion, said burner pipe adapted to distribute oil above said air openings, said ends provided with alined notches, 10 a rod slidably mounted within said notches, a plurality of blaze deflecting plates secured to said rod, said rod adapted to be shifted to move said plates above said air openings whereby the blaze from each burner portion 15 will be deflected, said casing being provided with a separate and independent air supply for each air opening.

7. An oil burner comprising a casing having a reduced forward portion, said reduced 20 forward portion being provided with air openings, said reduced forward portion provided with vertically extending ends, said ends extending for a spaced distance above said reduced forward portion, a burner pipe resting upon the upper portion of said reduced forward portion of said casing so as to extend across said air openings, said burner pipe adapted to supply oil for the 25 oil burner, means formed within said casing for supporting combustion, a plurality of movable oil deflecting plates supported by said casing, said oil deflecting plates provided with flanges around their outer edges, said flanges being opened at their inner 30 ends, each plate also provided with a central opening, said casing provided with a trough upon its forward portion, said oil deflecting 35

plates adapted to be moved above said air openings whereby the oil from said burner pipe may pass through the openings formed 40 in said oil deflecting plates at which time the oil will be caught by the plates and conveyed to said trough for allowing the oil to be passed to the end portions of the casing.

8. An oil burner comprising a casing, said casing provided with a reduced forward portion having air openings formed therein, vertical ends formed upon said reduced forward portion, a burner pipe resting upon the upper surface of said reduced forward 50 portion and extending across said air openings, means formed in said casing for supplying said air openings with independent air supplies for supporting combustion, a crank arm pivotally secured to said ends, a 55 plurality of oil deflecting plates fixed to said crank arm, said oil deflector plates provided with flanges upon their outer edges, said flanges being open at their inner ends, each plate also provided with a central opening, 60 said crank arm adapted to be swung so as to move said oil deflecting plates over the oil openings, a trough formed upon said casing, the inner ends of said plates being swung so as to allow their inner ends to communicate 65 with said trough whereby superfluous oil may pass through said central openings and fall upon said plates at which time the oil will run from said plates into said trough and be conveyed to a desired position by said 70 trough, said arm being adapted to swing said plates to an inoperable position when desired.

In testimony whereof I hereunto affix my signature in presence of two witnesses.

LUTE E. HINES.
